INSULATED JUG OR THE LIKE

Tony E. Branscum, ½ Gott Mfg. Co., Inc., P.O. Box 702,
Winfield, Kans. 67156

Filed June 6, 1966, Ser. No. 2,571

Term of patent 14 years

(Cl. D44—1)

FIG. 1

FIG. 2

FIG. 3

FIG. 4

FIG. 1 is a front elevational view of an insulated jug or the like, showing my new design;

FIG. 2 is a rear elevational view;

FIG. 3 is a side elevational view; and

FIG. 4 is a top plan view thereof.

The characteristic feature resides in the particular configuration of the cover and handle portions on a generally cylindrical container, all as shown.

The side opposite that seen in FIG. 3 is a mirror image of the side shown.

I claim:

The ornamental design for an insulated jug or the like, substantially as shown and described.
